UNITED STATES PATENT OFFICE

154,865

DESIGN FOR A HAND TRAP FOR THROWING CLAY BIRDS

Charles R. Mellen, Geneva, N. Y.

Application September 29, 1947, Serial No. 141,643

Term of patent 7 years

(Cl. D34—5)

To all whom it may concern:

Be it known that Charles R. Mellen, a citizen of the United States of America and resident of Geneva, in the county of Ontario and State of New York, has invented a new, original, and ornamental Design for a Hand Trap for Throwing Clay Birds, of which the following is a specification, reference being had to the accompanying drawings, forming part thereof.

Fig. 1 is a front elevational view of a hand trap for throwing clay birds, showing my new design, and

Fig. 2 is an edge view thereof.

The opposite side of the hand trap from that shown in Fig. 1 has an appearance which is substantially a reverse or mirror image of the side shown in Fig. 1.

What is claimed is:

The ornamental design for a hand trap for throwing clay birds, substantially as shown and described.

CHARLES R. MELLEN.
